CLAIM

The ornamental design for an audio player, as shown and described.

DESCRIPTION

FIG. 1 is a perspective view of an audio player showing my new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof; and,

FIG. 7 is a rear elevational view thereof.

The broken lines illustrating portions of the projector form no part of the claimed design. The dot-dash broken lines define the boundaries of the claimed design and form no part of the claimed design.

1 Claim, 6 Drawing Sheets
